UNITED STATES PATENT OFFICE

116,244

DESIGN FOR A BEDSTEAD

Sarah P. Shurcliff, New York, N. Y., assignor to Heywood-Wakefield Company, Gardner, Mass.,
a corporation of Massachusetts

Application December 9, 1938, Serial No. 81,669

Term of patent 3½ years

To all whom it may concern:

Be it known that I, Sarah P. Shurcliff, a citizen of the United States and a resident of New York, county of New York, and State of New York, have invented a new, original, and ornamental Design for a Bedstead, of which the following is a specification, reference being had to the accompanying drawing, forming a part thereof, in which—

Fig. 1 is a perspective view of a bedstead showing my new design, Fig. 2 is a fragmentary detail view in elevation, on an enlarged scale, of a part of the paneling of one of the ends of the bedstead, and Fig. 3 is a detail sectional view, on a further enlarged scale, through that part of the paneling shown in Fig. 2 and as taken on the line 3—3 of said Fig. 2.

I claim:

The ornamental design for a bedstead, substantially as shown.

SARAH P. SHURCLIFF.
